UNITED STATES PATENT OFFICE.

HOWARD L. WEED, OF DETROIT, MICHIGAN, ASSIGNOR TO WEED DIFFERENTIAL-ROTARY MOTOR COMPANY, OF DETROIT, MICHIGAN, A CORPORATION OF SOUTH DAKOTA.

ROTARY ENGINE.

1,348,675.

Specification of Letters Patent. Patented Aug. 3, 1920.

Application filed August 3, 1918. Serial No. 248,186.

To all whom it may concern:

Be it known that I, HOWARD L. WEED, a citizen of the United States, and residing at Detroit, in the county of Wayne and 5 State of Michigan, have invented a new and Improved Rotary Engine, of which the following is a specification.

The present invention has reference to an engine of the rotary alternating piston 10 type, one of its objects being to provide a noiseless, efficient and inexpensive means for driving the shaft from the rotors.

Another object is to provide a rotor the bearings for which are spaced from each 15 other lengthwise of the shaft and located on opposite sides of the central plane of the annular cylinder, whereby a more rigid and reliable construction is secured than has been possible heretofore.

20 Again, the invention consists in means for applying to the sealing ring carrier a predetermined fluid pressure on the side thereof farthest from the corresponding rotor, whereby the carrier is pressed against 25 the rotor to maintain a close joint; it also consists in means for applying such fluid pressure to a sealing ring supported in the carrier; also in means for relieving the pressure to prevent it from becoming great 30 enough to create excessive friction.

The invention also comprises means for pumping cooling fluid, preferably oil, through those portions of the rotors which are nearest the firing chamber.

35 The invention further consists in certain means for sealing the joints between the pistons of one rotor and the circumferential face of the other rotor; also in certain details of the piston construction.

40 It also consists in means whereby the exhaust from one engine cylinder is utilized to draw air into a second cylinder for scavenging purposes.

The invention further consists in certain 45 details of construction shown, described and claimed.

In the drawings, Figure 1 is a side view, parts being broken away, showing one embodiment of the invention. Fig. 2 is an enlarged section showing the by-pass through 50 which a low pressure is transmitted from the cylinder to the side of the sealing ring farthest from the corresponding rotor. Fig. 3 is a view on the line 3-3 of Fig. 1,

the left hand section of the casing being removed; ignition has just taken place at one side whereas exhaust is beginning at the other. Fig. 4 is an enlarged fragmentary section corresponding to Fig. 1. Fig. 5 is a section similar to Fig. 3, the rotors being in 55 about the mid-point of a stroke. Fig. 6 is a longitudinal section of a piston, one head being removed. Fig. 7 is a section on line 7-7 of Fig. 6. Fig. 8 is an enlarged section on line 8-8 of Fig. 6. Fig. 9 is a bottom plan view corresponding to Fig. 8. Fig. 10 is a side view of the main shaft and the fly wheels, parts being broken away. Fig. 11 is a section on line 11-11 of Fig. 10. Fig. 12 is a side view of the crank shaft 70 and one of the associated pinions, the parts being disassembled. Fig. 13 is an end view of the crank shaft. Fig. 14 is a side view of one of the rotors, parts being broken away and the piston heads being omitted. Fig. 15 is a section on line 15-15 and Fig. 16 is a similar fragmentary section on line 16-16 of Fig. 14, both showing but the main element of the rotor only. Fig. 17 is a section on the line 17-17 of Fig. 14. Fig. 80 18 is an end view of the second element of the rotor. Fig. 19 is a side view of the engine, parts being broken away to show the exhaust pipe construction. Fig. 20 is a section on line 20-20 of Fig. 19. Fig. 21 is 85 an enlarged fragmentary view corresponding to Fig. 3 and showing the pump valve whereby the oil, which surges back and forth in the rotor, is deflected or returned to the casing. 90

Power transmitting features.—The invention is shown applied to a two cylinder engine although a greater or less number may be employed. In the type shown, each cylinder casing is formed in two sections 1 95 and 2, formed in any suitable way, the sections 2 being bolted together as by cap screws 3. The main shaft 4 extends from end to end and is supported in the bosses 5 on the sections 1. Rigidly secured on the 100 shaft within each casing unit, for example, by means of the keys 6, is a fly wheel 8 having a long hub into which the shaft is fitted and through which the roller bearing 9 the weight of the rotating parts is transmitted to the casing. As shown, a single bushing 10 is interposed between the hub of the flywheel and the bearings 9 as well as 105

between said hub and similar bearings 11 and 12 upon which the corresponding elements of the two rotors, hereinafter described, turn; at the opposite end of the cylinders, the bearings 13 and 14 and the bushing 15 correspond, respectively, to the parts 11, 12 and 10, but the bearing 9 is preferable superseded by a thrust bearing 16 whereon the thrust of the flywheels and sleeves is taken. The joints around the bearings 9 are sealed by suitable glands 18

It will be seen that each flywheel includes a rim 19 and four arms 20 (between which are formed openings 21, Fig. 11) which are 15 perforated at points 22—23 ninety degrees apart; diametrically disposed pairs of the perforations are extended in opposite directions from the arms, being formed in bosses 24—25 as best indicated in Figs. 10 20 and 11. As is best indicated in Fig. 10 corresponding parts of the two fly wheels are spaced forty-five degrees from each other about the shaft. Each perforation receives a bearing or bearings 26 (Fig. 1), 25 preferably of the roller type, in which is mounted a crank shaft 27 upon one end of which a corresponding gear or pinion 28 is fixed. Any suitable means for securing these gears to the crank shafts may be used, 30 that shown (Fig. 12), namely the keys 29 and retainer 31 is claimed in my above identified application.

Those crank shafts which are disposed in the perforations 22 have their gears mounted 35 on the right hand end, Figs. 1 and 10, and arranged to mesh with the gear or circular rack 32 fixed on an annular flange 33 formed as a part of the casing section 1; in like manner, the crank shafts for the holes 23 40 (Fig. 11) have their gears meshing with a similar rack or gear 34 on the section 2. Thus it is evident that if the flywheel and shaft are to turn, the gears and crank shafts must also rotate. Each crankshaft (Fig. 45 12) has a crank 36, and these cranks are, of course disposed alternately on opposite sides of the plane which includes the axis of the corresponding cylinder, as explained with reference to the gears.

50 Mounted on the bearings 11—14 and 12—13 are pairs of rotors—"rights" and "lefts"—the construction of the latter being shown in Figs. 14 to 18 inclusive. As indicated therein, the rotor preferably comprises 55 a main disk-like member or element having an offset hub 41 received on the bearing 13 and connected to the rim 42 by an offset web 43 provided with openings 44—45 spaced ninety degrees apart. The outer face 46 of 60 the rim is cylindrical except in so far as it is broken by the oppositely disposed pistons, hereinafter described; and the central portion of the web flares inwardly from the inner end of the bearing 13 as shown at 48. 65 At points midway between the openings

44—45 the web is provided with bosses 49 cored out at 50 to receive nuts 51 into which the screws 52 are threaded, these screws serving to hold the second element 53 of the rotor firmly on the first. The construction 70 of this element is best shown in Figs. 17 and 18, and it is carried (Fig. 11) on the bearing 12 on the opposite side of the web of the flywheel: thus the rotor is supported at two points well removed from each other 75 longitudinally of the shaft and on opposite sides of the central plane of the cylinder. It will be understood that the elements 49 pass through the openings 21 between the arms of the flywheel. 80

As stated above the other rotor differs from that described merely in that it is a "right" instead of a "left," and the corresponding parts, in so far as they are shown, are therefore given the same reference 85 numeral qualified by a prime. The bosses of the second rotor pass through the openings 21 at right angles to those in which the first mentioned bosses are received. It will also be understood that the cranks 36 90 are received in the openings 44 of the corresponding rotor, the corresponding hubs 24 or 25 passing through the openings 45. As shown, the openings 44 are approximately 95 elliptical to provide clearance for the cranks, but the outer wall of the openings 45 extend more nearly circumferentially of the rotor to accommodate the circumferential movement of the rotor relatively to the hubs. The cranks 36 are connected to the corresponding rotor by means of connecting rods 100 or links 54 pivoted at 55 between the main web portion of two of the arms 43 and the lugs 56 thereon.

The intake port leading to the annular cylinder 55 in which the pistons travel appears at 57; the exhaust port at 58, Figs. 3 and 5; and the spark plug or other ignition means at 59.

The general operation is as follows, the direction of rotation being clockwise, Figs. 3 and 5; when the rear face of a leading or first piston sweeps by the intake port 57 its motion is rapidly increasing as compared with that of the next succeeding or second piston, consequently a suction is set up in the space between these particular pistons and air (in this case, fuel mixture) is drawn in. (Fig. 3) As the second piston sweeps by the intake port, the relation of the speed of the rotors is reversed thereby compressing the air or charge, an action which is completed when the charge reaches the ignition means 59. Firing taking place, the first piston is again forced forward at relatively high speed until exhaust occurs as shown in Fig. 3, whereupon the second piston again moves faster than the first; and the exhaust is followed by a scavenging of the space between the two pistons during 110 115 120 125 130

approximately the next quarter turn of the shaft, as hereinafter more fully explained. In this movement the gears 28 ride around on the racks 32-34, and the cranks, acting 5 on the varying leverages which they form with the links 54, react on the flywheel to drive the shaft. There being four pistons, it follows that four working strokes per cylinder are secured for each revolution. It 10 is preferred to arrange the corresponding working parts of the two cylinders at forty five degrees to each other, as stated before, so that the impulses in one cylinder overlap those in the other, that is, in a two cylinder engine an impulse is secured each forty five degrees of angular movement of the shaft.

When the parts are constructed as shown, the maximum speed of the forward piston 20 relatively to the rear piston on working stroke occurs when the stroke is only about one third completed, that is, while the pressure is still high. Putting it another way, the greatest leverage on the flywheel and 25 shaft is secured when the pressure is high; and as the torque is a product of these two factors it follows that a more efficient application of power is thus attained.

Scavenging and piston cooling.—It will 30 be seen, Figs. 6 and 7 that the pistons each comprise skeleton end walls 60-61 joined by a longitudinal imperforate wall or diaphragm 62, there being side openings 63 between the wall 62 and the rim of the corresponding rotor, these openings being arranged to register, after exhaust is completed, with air inlets 64 (Figs. 3 and 5) in the sides of the cylinder. The piston heads 65 are detachably secured to the walls 35 60-61 as by threaded studs 66 and are provided with ribs 68 whereby the passages 69 are formed. The outer walls of the pistons are open at 70. Each of the cylinders has a scavenging port 72 between the ports 56 and 40 57, said ports 72 opening into the scavenging pipe or manifold 73, Figs. 19 and 20. The exhaust ports 57 open into the pipe or fitting 74 that includes the dividing wall 75 whereby the exhaust gases from the two 45 50 cylinders are kept separate until they are well beyond the exhaust port which is nearest the outlet end of the fitting. The pipe 74 projects into the manifold 73 and has its extreme edge close to the inner wall thereof, but is spaced considerably therefrom nearer 55 the exhaust ports, whereby the flow of exhaust gases from the fitting creates a suction in the manifold 73 and in the port 72. As the exhaust impulses from the two cylinders overlap, it is evident that sub-atmospheric pressure is constantly maintained in the manifold 73, therefore as soon as the opening 70 registers with the port 72 and the openings 63 register with the air inlets 64, cold air is drawn in through the piston 60 65

as indicated by the arrows Fig. 5, thereby blowing out whatever hot gas may be present and cooling the piston. In order to prevent the air from seeping across from the space interiorly of the wall 62 to the 70 space exteriorly thereof, it is preferred to provide one or more interrupting longitudinal grooves 79, Fig. 3, in the outer surface of the piston.

Sealing features.—Interposed between 75 the outer edges of the rotors is a ring 80, Figs. 1 and 4, substantially V-shaped in cross-section that rides rather loosely on the rim of the flywheel. This ring not only seals the joint but also reduces friction, 80 since it itself moves around on the flywheel by a motion dependent on the relative movement of the rotors.

The joints between the piston of one rotor and the surface 46 or 46' of the other preferably closed as indicated in Figs. 6, 7, 8 and 9, that is, by continuing the piston ring groove 82 across the inner face of the piston and mounting therein the plates 83-84 that are forced down onto the surface 46 or 46' 90 and outwardly against the surfaces 85 and 86 and the ends of the piston rings 88 by means of the centrifugal levers 89 pivoted in the piston at 90 and having overweighted ends 91, and the pivoted wedge 92. Only 95 sufficient overweight is employed to insure a close fit at normal engine speeds.

The sections 1 and 2 are provided adjacent the rim of the corresponding rotor with grooves, Figs. 1 and 4, preferably having the 100 tapering outer walls 93 and in these grooves are received annular sealing ring carriers 94 that fit closely to the face of the corresponding rotor and carry suitable sealing rings 94' 94'' bearing on the walls of the 105 grooves. At a point swept over by the rearward piston of a given pair when the compression of the charge has proceeded to a small extent, say to four pounds per square inch, the walls of the cylinder are perforated at 95, Figs. 2 and 3, to receive the check valves 96 access to which may be had by removing the plugs 97 which also act as limits for the opening movements of the valves. The openings 95 communicate with 110 the space or the rear sides of the ring carriers, as by means of the small pockets 98 and passages 99. As soon as the rearward piston sweeps over the openings 95, the admission of higher pressure is precluded but 115 the air in the pockets cannot escape since the check valves 96 are thereafter automatically seated, consequently the ring carriers 94 are forced against the rotors by a pressure sufficient to secure a proper sealing action 120 and yet not great enough to induce objectional friction. It will be understood that the rings are gradually carried around in the carrier; by piercing the carriers at 100, Fig. 4, this movement is utilized to occa- 125 130

sionally relieve the pressure in the pockets 98, since the excess gas then passes through between the ends of the rings, the passage 100 and inwardly along the face of the corresponding rotor until it escapes into the gear chamber. Oil is fed to the joint between the base of the ring 80 and the flywheel through the passages 101 in the latter by centrifugal action; and excess oil escaping from the joint or which follows the flywheel, gets into the space between the ring 80 and the rotors and passes into the chambers 105, hereinafter described, through ports 102.

15 *Rotor cooling features.*—It will be observed that each rotor rim is cored out to form a circumferential chamber 105 into which oil is thrown through the passages 106, Figs. 4 and 17 by centrifugal force. 20 Were no means provided to prevent it, these chambers would therefore quickly fill with oil and remain filled. The variation in the angular speed of the motor at different points in the stroke is utilized to constantly 25 pump the oil out of the chamber and return it to the casing by the following means: at diametrically opposite points the chamber is divided by a wall 109—110, Figs. 3 and 21, into an outer passage 111 and two inwardly 30 inclined passages 112—113 which lead, respectively, to the outlets 114—115 formed in a valve casing 116 that is supported in the depression or valve chamber 118, Fig. 16, formed in a boss 119 on the corresponding 35 main rotor element. A valve 120 is slideable in the chamber 118 circumferentially of the rotor and closes one or the other but not both of the ports 114—115, depending on its position. For example, as a particular rotor 40 accelerates, the inertia of the oil in the chamber 105 causes it to flow backward relatively to the rotor, whereupon the excess oil is deflected inwardly through the passages 112. The acceleration, together with the inertia of 45 the oil (which acts by pressure through the passages 112 and by suction through the passages 113), throws the valves 120 backwardly thus opening the port 114 and permitting the oil to escape inwardly into the casing; in 50 like manner, as the rotor slows down in its stroke, the valves 120 are thrown to the other limits of their movement, thereby opening the ports 115 and allowing the oil in the chamber 105 to escape through the passages 55 113 and 115. A constant circulation is thus maintained to and from the chamber 105.

Oil is largely prevented from seeping through the joints, between the rotors and the ring 80 by the ribs 122, Figs. 4 and 17, 60 and by the passages 102 through which it escapes into the chamber 105, as stated above.

The fuel mixture may be supplied by a suitable carburetor 125, Fig. 19, which is provided with warm fuel through the pipes

126—127 and the heating chamber 128 65 formed in the exhaust manifold 74.

Cooling water is supplied to the several water passages 130 in the casing by means of the inlet pipe 131, Fig. 19, and is discharged therefrom through the pipe 132. 70

The various features involved are each susceptible to considerable change without departing from the spirit of the invention, and some of these features, for example, the rotor construction and the means for connecting the rotors to the shaft, are applicable to steam engines as well as to those of the combustion type; I do not, therefore wish to be limited except as indicated by the subjoined claims. 75

I claim:—

1. A rotary engine comprising a casing, a main shaft mounted therein, said casing including an annular cylinder, a pair of rotors angularly movable about the main shaft, each of the rotors including a pair of pistons arranged to travel in the cylinder, the pistons of the two pairs alternating, a crank shaft carrier between the rotors and rigid with the main shaft, crank shafts 90 mounted in said carrier, and having their axes parallel to that of the main shaft, said crank shafts each having a gear on one end and a crank on the other and alternate crank shafts being reversely arranged, gears fixed to the casing and with which the first named gears are in mesh, and a link connecting each crank with the rotor which is on the same side of the crank shaft carrier. 95

2. A rotary engine comprising a casing, a main shaft mounted therein, said casing including an annular cylinder, a pair of rotors angularly movable about the main shaft, each rotor including a pair of pistons arranged to travel in the cylinder, the pistons of the two pairs alternating, a counter shaft carrier between the rotors and rigid with the main shaft, counter shafts supported by the carrier, means associated with the counter shafts whereby a relative 100 angular movement of the rotors is made to turn the carrier and main shaft, said rotors each being supported on both sides of the counter shaft carrier. 110

3. In a rotary engine, a casing forming 115 an annular cylinder, a main shaft perpendicular to the plane of the circular axis of said cylinder at the center of the circle, a pair of rotors movable about the shaft and each including a pair of pistons arranged 120 to travel in the cylinder, the pistons of the two pairs alternating, means whereby a relative angular movement of the rotors is made to cause the main shaft to turn, and bearings for supporting each rotor on both 125 sides of the plane of the axis of the cylinder.

4. A rotary engine comprising a casing, a main shaft mounted therein, said casing

5 forming an annular cylinder, a pair of rotors loose on the shaft and each including a pair of pistons arranged to travel in the cylinder, the pistons of the two pairs alternating, a fly wheel fixed on the shaft and disposed between the rotors, means whereby a movement of the rotors angularly relative to each other causes the flywheel to turn, said flywheel having openings therein 10 through which the rotors pass, and bearing means for each rotor on both sides of flywheel.

15 5. A rotary engine including an annular cylinder, a main shaft, a pair of rotors movable about the shaft and each having a pair 20 of pistons traveling in the cylinder, the pistons of the two pairs alternating, a flywheel disposed between the rotors, crank shafts carried by and rotatable in respect to the flywheel, links connecting the cranks of alternate crank shafts to different rotors, and means for causing the crank shafts to rotate as the rotors travel in the cylinder, whereby the flywheel and shaft are caused 25 to turn.

30 6. An internal combustion engine including a casing forming an annular cylinder, there being a pocket adjacent said cylinder and a restricted passage for admitting fluid pressure from the cylinder to the pocket, a 35 rotor for the cylinder, the casing having an annular groove therein opening toward the outer edge of the rotor, a sealing member in the groove, the bottom of the groove communicating with the pocket, whereby pressure in the pocket forces the sealing member against the rotor.

40 7. An internal combustion engine comprising a casing forming an annular cylinder, pistons in the cylinders, rotors whereby the pistons are respectively carried, means for admitting fuel mixture to the cylinder between the pistons means for causing the pistons to compress the mixture, 45 a sealing element for the joint between one of the rotors and the casing, a passage leading from the cylinder at a point swept over by the rearward piston when the compression is low, said passage also leading to the 50 side of the sealing element opposite from the rotor whereby said element is pressed against the rotor.

55 8. An internal combustion engine including a casing forming an annular cylinder, a rotor for the cylinder, the casing having an annular groove adjacent the outer edge of the rotor and opening toward said rotor, a sealing ring carrier in the groove and bearing on the rotor, a sealing ring supported thereby and bearing on the wall of the groove, and a passage connecting the cylinder to a point in the groove beyond the sealing ring, whereby the ring carrier 60 is pressed over against the rotor by fluid pressure.

9. An internal combustion engine including a casing forming an annular cylinder, a rotor for the cylinder, the casing having an annular groove adjacent the outer edge of the rotor and opening toward said rotor, 70 a sealing ring carried in the groove and bearing on the rotor, a sealing ring supported thereby and bearing on the wall of the groove, and a passage connecting the cylinder to a point in the groove beyond the sealing ring, whereby the ring carrier is 75 pressed over against the rotor by fluid pressure, and means for intermittently relieving the pressure in said passage.

10. An internal combustion engine comprising a casing forming an annular cylinder, pistons in the cylinder, rotors whereby the pistons are respectively carried, means for admitting working fluid to the cylinder between said pistons, the casing having an 80 annular groove therein adjacent the outer edge portion of one of the rotors, said groove opening toward the said rotor, a sealing ring carrier in the groove and pressing on the rotor, a sealing ring supported 85 by the carrier and pressing on the wall of the groove, and a passage connecting a point of low pressure in the cylinder to a point in the groove beyond the ring, whereby the carrier is lightly pressed against the rotor. 90

11. An internal combustion engine comprising a casing forming an annular cylinder, pistons in the cylinder, rotors whereby the pistons are respectively carried, means for admitting working fluid to the cylinder 100 between said pistons, the casing having an annular groove therein adjacent the outer edge portion of one of the rotors, said groove opening toward the said rotor, a sealing ring carrier in the groove and pressing 105 on the rotor, a sealing ring supported by the carrier and pressing on the wall of the groove, and a passage connecting a point of low pressure in the cylinder to a point in the groove beyond the ring, whereby the carrier 110 is lightly pressed against the rotor, and a check valve in said passage whereby fluid in the passage is prevented from returning to the cylinder.

12. In combination, a rotor having a hole low rim portion forming a circumferentially extending chamber, means for supplying liquid to said chamber, means for constraining the rotor to turn alternately faster and slower, and means controlled by the inertia 115 of the liquid for directing the liquid from said chamber inwardly toward the axis about which the rotor turns.

13. A rotary engine comprising a casing, an engine shaft mounted therein, said casing 125 including an annular cylinder, a pair of rotors concentric with and loose on the shaft, each of said rotors including a pair of pistons arranged to travel in the cylinder, the pistons of the two pairs alternating, means 130

- for supplying a charge of combustible mixture to the space between two adjacent pistons, means for igniting the charge whereupon the expansion of the charge forces the 5 pistons forward at different speeds, the speed of the forward piston being greatest for a time and the relation of the speeds thereafter reversing, the rotors having circumferential chambers therein around their 10 outer edges to which cooling liquid is supplied as the rotors turn, and means whereby the changing angular speed of the rotors is made to expel the liquid from said chambers and return it toward the shaft.
- 15 14. A rotary internal combustion engine comprising two annular cylinders, a pair of rotors for each cylinder, each rotor including a pair of pistons and the pistons of the pairs alternating, the pistons being hollow, 20 means for exhausting burned charges from between the adjacent pistons, and means for utilizing the exhaust gases from each cylinder for scavenging the pistons of the other cylinder.
- 25 15. A rotary internal combustion engine comprising two annular cylinders, and hollow pistons arranged to travel therein, means for supplying fuel mixture to the cylinders between the pistons, means for igniting the mixture, exhaust passages including 30 parts through which the burned gases escape, air ports entering the cylinders beyond

the exhaust ports, scavenging ports beyond the exhaust ports, and means for utilizing the exhaust gases to maintain a sub-atmospheric pressure in said scavenging ports whereby air is drawn through the pistons and air ports for cooling purposes. 35

16. In a rotary engine, a casing forming an annular cylinder, a pair of rotors each 40 having a piston received in the cylinder, and means for sealing the joint between the piston of one rotor and the other rotor, said means comprising a pair of elements constructed and arranged to be spread apart 45 longitudinally of the common axis of the rotors to thereby approach the adjacent walls of the cylinder, and centrifugal means for thus causing said elements to spread.

17. In a rotary engine, a casing forming 50 an annular cylinder, a pair of rotors each having a piston received in the cylinder, fractional piston rings for the pistons and means for sealing the joint between the piston ring of one of the rotors and the other 55 rotor, comprising a pair of elements constructed and arranged to be spread apart longitudinally of the common axis of the rotors and against the ends of the piston ring, and a centrifugally operated lever carried by the piston, whereby said elements 60 are thus spread apart.

HOWARD L. WEED.
